Des. 238,351

Patented Jan. 6, 1976

238,351

VAN STORAGE ENCLOSURE

William M. Bell, 17456 Mission Blvd., Granada Hills, Calif. 91344, and James H. Dissman, Jr., 1917 W. Mountain St., Glendale, Calif. 91201

Filed Oct. 9, 1974, Ser. No. 513,272

Term of patent 14 years

Int. Cl. D12—16

U.S. Cl. D12—156

FIG.1

FIG.2

FIG.3

FIG.4

FIG. 1 is a perspective of a van storage enclosure showing our new design, it being understood that the broken lines are for illustrative purposes only;

FIG. 2 is a top plan view thereof;

FIG. 3 is a front elevational view thereof; and

FIG. 4 is a side elevational view thereof.

We claim:

The ornamental design for a van storage enclosure, as shown.
